STOCKING

Stanley Sell, Stroudsburg, Pa., assignor to Holiday Hosiery Corp., New York, N. Y., a corporation of New York

Application March 8, 1951, Serial No. 14,418

Term of patent 14 years

(Cl. D47—7)

To all whom it may concern:

Be it known that I, Stanley Sell, a citizen of the United States, resident of Stroudsburg, in the county of Monroe, State of Pennsylvania, have invented a new, original, and ornamental Design for a Stocking, of which the following is a specification, reference being had to the accompanying drawing, forming part hereof.

In the drawing,

I claim:

The ornamental design for a stocking, substantially as shown.

STANLEY SELL.
